DESIGN FOR A KEYHOLE ILLUMINATOR

Jack C. Helm, Oakland, Calif.

Application March 14, 1936, Serial No. 61,637

Term of patent 7 years

To all whom it may concern:

Be it known that I, Jack C. Helm, a citizen of the United States, residing at Oakland, in the county of Alameda and State of California, have invented a new, original, and ornamental Design for a Keyhole Illuminator, of which the following is a specification, reference being had to the accompanying drawing, forming part thereof.

Figure 1 is a side elevational view of the keyhole illuminator showing my new design.

Figure 2 is a front elevational view.

Figure 3 is a top plan view.

Description: The stippled hemispherical portion of the lamp represents an opaque coating thereon.

I claim:

The ornamental design for a keyhole illuminator substantially as shown and described.

JACK C. HELM.
